ACOUSTIC TILE

Clayton A. Laughlin, Minneapolis, Minn., assignor to
Wood Conversion Company, St. Paul, Minn., a corpo-
ration of Delaware

Application February 27, 1958, Serial No. 49,838

Term of patent 14 years

(Cl. D18—2)

Fig. 1

Fig. 2.

Fig. 3

Fig. 1 is a top plan view of an acoustic tile showing my new design;

Fig. 2 is an edge view thereof; and

Fig. 3 is a fragmentary enlarged cross-section on line 3—3 of Fig. 1.

I claim:

The ornamental design for an acoustic tile, substantially as shown.
